UNITED STATES PATENT OFFICE.

WILLARD M. WISE, OF SOUTH WILLIAMSPORT, PENNSYLVANIA.

SIGNALING APPARATUS.

Application filed March 13, 1926. Serial No. 94,475.

This invention relates to a signaling apparatus and it is an object of the invention to provide an apparatus of this kind especially adapted for use within a building and which is operable from any floor of the building to give visual indication on each of the floors of the approximate location of a fire or the like and which also comprises means to operate a bell or other audible signal to give a sound alarm.

It is also an object of the invention to provide an apparatus of this kind embodying an indicating means operable from any one floor of a building to give indication at each of the floors of the approximate location of a fire or the like, together with a reel upon which a hose of desired length is normally wound, said reel being locked against rotation when the indicator is idle and said reel being automatically released when the indicator is operated.

Another object of the invention is to provide an apparatus of this kind which is normally inoperative, together with a normally locked reel, said reel having wrapped therearound a portion of a hose extending downwardly through all of the floors and in communication with a suitable source of water supply, said hose upon release of the reel being readily withdrawn from said reel at any one of the floors.

Furthermore, it is an object of the invention to provide an apparatus of this kind operating to give a similar signal upon the various floors of a building, said signal being operable from any one of the floors, together with a hose normally coupled to a source of water supply and readily accessible at each of the floors, the flow through such hose being normally closed by a valve, said valve having means associated therewith permitting the valve to be operated from any one of the floors.

The invention consists in the details of construction and in the combination and arrangement of the several parts of my improved signaling apparatus whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in vertical section and of a diagrammatic character taken through a building structure illustrating a signaling apparatus constructed in accordance with an embodiment of my invention;

Figure 2 is a sectional view taken substantially on the line 2—2 of Figure 1;

Figure 3 is an enlarged sectional view taken substantially on the line 3—3 of Figure 1, illustrating one of the indicating units herein embodied;

Figure 4 is a view partly in front elevation and partly in section of the structure as illustrated in Figure 3;

Figure 5 is a view in top plan of one of the audible signals herein employed;

Figure 6 is a fragmentary view partly in end elevation and partly in section of the reel and associated structure as herein disclosed;

Figure 7 is a fragmentary view in elevation illustrating the coupling with the nozzle 80 end of the hose for returning the same to the reel;

Figure 8 is a view in perspective of the attaching member shown in Figure 7.

As disclosed in the accompanying drawings, B denotes a building of any desired number of floors and which has extending within the lower floor or cellar a water pipe or stand 1 in which is interposed a valve 2 of any desired type and which is adapted to be moved into open or closed position upon requisite rotation of the operating wheel 3.

Suitably coupled, as at 4, to the pipe or stand 1 is a hose H of any desired type but preferably of a kind used for fire purposes. Normally this hose H extends upwardly of the building through the openings 5 suitably positioned at the floors 6, the upper end portion of the hose being normally wound around the reel R. This reel R is of a conventional flanged type and is rotatably supported, as at 7, by a wall of the building or other suitable support. The inner flange 8 of the reel is provided with the continuous brake drum 9 concentric to the axis of the reel and with which normally engages the pivoted brake shoe 10 constantly urged into close frictional contact with the drum 9.

through the medium of the retractile spring 11. This brake shoe 10 serves to prevent wild rotation of the reel R and thereby assuring a more effective unwinding of the hose 5 from the reel when the occasion requires.

The outer flange 12 of the reel R, as herein disclosed, is provided adjacent to the periphery thereof with an outstanding handle member or grip 14 to facilitate the winding of 10 the hose upon the reel. It will be readily understood that when the reel R is free to rotate the hose may be readily withdrawn from the reel for use at any one of the floors.

The reel R or more particularly the inner 15 flange 8 also carries a ratchet wheel 15 with which is adapted to be engaged a sliding bolt 16 whereby the reel R may be normally held against rotation and thus prevent withdrawal of the hose H therefrom. The bolt 20 16 is adapted to be automatically released from the ratchet wheel 15 in a manner to be hereinafter more particularly referred to.

Suitably supported within the upper floor 25 of the building is an idle pulley 17 around which passes an endless cable 18. The stretches of this cable 18 are disposed through suitable openings 19 in the various floors 6 to permit the cable 18 to be operatively engaged with the wheel 3 hereinbefore 30 referred to. The cable 18 preferably has interposed therein a retractile spring 20 in order to assure the cable 18 being maintained taut. When it is desired to cause the water to flow through the hose H, a stretch 35 of the cable 18 may be properly pulled at any one of the floors to effect the requisite rotation of the wheel or pulley 3 to open the valve 2.

Suitably positioned within each of the 40 floors of the building is a casing C provided with a window 21 through which is adapted to be exposed an indication 22, said indication serving to denote a particular floor of the building or, if preferred, a particular part of such floor, as second floor front, 45 second floor rear, etc.

Mounted within the casing C above and 50 below the window 21 are the drums 23 about which are adapted to be wound the end portions of a web 24. On this web 24 are suitably produced the indications 22. The shafts 25 for the drums 23 extend exteriorly 55 beyond a side of the casing C and are provided with the gear wheels 26 meshing with an intermediate gear 27 fixed to a shaft 28 rotatably supported by the adjacent side wall of the casing C. This shaft 28 also has fixed thereto a pulley 29 which is coupled by an endless belt 30 with a substantially 60 similar pulley associated with the casing C on the adjacent floor and so on. Upon requisite pull on any one of the cables 30 the webs 24 within the casings on all of the floors will be caused to move in unison and 65 to an extent to expose through the windows

21 a similar indication 22 in order that parties on the various floors may readily approximate in what part of the building there may be a fire or other cause for alarm.

The outer end portion of the bolt 16 is operatively engaged with a bell lever 31 suitably supported for swinging movement, a free leg of said lever 31, when the bolt is in locking engagement with the ratchet 70 wheel 15, immediately underlies a block or enlargement 32 fixed to a stretch of the adjacent belt 30. As this stretch of the belt 30 is pulled downwardly to adjust the various webs 24 to give the particular locating signal, the block or enlargement 32 will impart requisite swinging movement to the bell crank lever 31 to pull the bolt 16 into release position, thus freeing the reel for rotation when pull is imposed upon the hose H at any one of the floors of the building.

A stretch of each of the belts 30 is also provided with a block or enlargement 33 which is normally positioned immediately above a trip 34 so that as such stretch of each of the belts 30 is moved to operate the webs 24 the trips 34 will be operated to release the bell A or kindred audible signal whereby a sound alarm will be created to notify the occupants of the various floors. The alarm A may be of any desired type, as for example, a spring operated bell or gong. As the particular construction of the alarm A in itself forms no part of the present invention it is not believed necessary that a detailed illustration and description thereof be given.

Each of the belts 30 preferably has interposed in a stretch thereof a retractile spring 35 to maintain said belt under requisite tension.

The free end portion of the hose H is provided with a nozzle N of desired type provided with an outstanding loop 36 with which is adapted to be engaged a hook member 37 of an attaching member M. This hook member 37 is provided at its end portion remote from the hook bill 38 with an eye member 39 with which is suitably connected, as at 40, an end portion of a cable 41. This cable is of a length to extend from the lower floor up to the reel to which it may be suitably attached. By use of this member M the cable 41 may be readily attached to the nozzle N and thus provide means whereby the hose to be used may be drawn upwardly, upon requisite rotation of the reel R, through the openings 5 in the floors 6 and rewound upon the reel R. This member M is provided with a leg 42 substantially parallel to the hook member 37 and which is adapted to be inserted within the nozzle, as illustrated in Figure 7, when the member M is in working engagement with such nozzle. This leg 42 serves to ef-

fectively maintain the member M against displacement during the period the nozzle N of the hose is being drawn upwardly.

The attaching member M may be applied to or removed from the nozzle N with ease. Furthermore, when the member M is engaged with a nozzle N said nozzle N will be lowered from the reel through different floors in a perfectly safe manner.

From the foregoing description it is thought to be obvious that a signaling apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with a building, a signal apparatus comprising a plurality of indicators positioned in different portions of the building, said indicators being provided with similar indicia, means operable from different portions of the building to effect a simultaneous operation of the indicators to bring into action a similar indication by all of the indicators, a hose reel, means for normally holding said reel against rotation, and means coacting with the last named means and the means for operating the indicators to release said last named means upon operation of said means for operating the indicators.

2. In combination with a building, a signal apparatus comprising a plurality of indicators positioned in different portions of the building, said indicators being provided with similar indicia, means operable from different portions of the building to effect a simultaneous operation of the indicators to bring into action a similar indication by all of the

indicators, a member for holding a supply of hose, means associated with said member for normally holding the hose against removal therefrom, and means coacting with said last named means and the means for operating the indicators to release said last named means upon operation of the means for operating the indicators.

3. In combination with a building having a plurality of floors, an indicator on each floor, each indicator having indicia similar to the indicia on the indicator of each of the other floors, means for bringing into action a common selected indication carried by all of the indicators, a reel rotatably supported on the upper floor of the building, means for normally holding said reel against rotation, a hose having its nozzle end portion normally wound upon the reel, a source of water supply within the lower floor of the building, said hose extending downwardly freely through the floors and coupled to said supply, and means for automatically releasing the reel upon operation of the indicators.

4. In combination with a building having a plurality of floors, an indicator on each floor, each indicator having indicia similar to the indicia on the indicator of each of the other floors, means for bringing into action a common selected indication carried by all of the indicators, a reel rotatably supported on the upper floor of the building, means for normally holding said reel against rotation, a hose having its nozzle end portion normally wound upon the reel, a source of water supply within the lower floor of the building, said hose extending downwardly freely through the floors and coupled to said supply, means for automatically releasing the reel upon operation of the indicators, a normally closed valve within the lower floor for controlling the flow from the water supply, and means operable from each of the floors to move said valve into open position.

In testimony whereof I hereunto affix my signature.

WILLARD M. WISE.
